UNITED STATES PATENT OFFICE

HENRY L. DOHERTY, OF NEW YORK, N. Y.

METHOD OF DEVELOPING OIL FIELDS

No Drawing. Application filed July 20, 1925, Serial No. 44,915. Renewed May 20, 1930.

This invention relates to the development of oil fields and more particularly to a method of extracting the oil from the oil bearing sands in such a manner that the expulsive force of the gas usually found with the oil may be utilized to the best advantage in extracting the oil from the sands and bringing it to the surface.

Unless an oil pool is controlled by a single operator, the wells are usually projected into the oil sands in a more or less haphazard manner without any particular regard to the character of the oil sands and the other factors governing oil production, each operator striving to be the first to get producing wells into the oil sands in order to profit by the flush production which usually follows when the wells are first entered into the producing sands. In other words, no particular system of control of the wells is practiced, each well being allowed to flow from the time it is entered in the oil bearing sands. Where a single operator has control of an oil pool, the method of oil production is not substantially different from that where more than one operator is entitled to enter the field, the primary difference being that not so many wells will be sunk in the field. However, such wells as are sunk in the field are allowed to flow from the time the oil bearing sands have been reached without regard to other wells which may subsequently be drilled into the same sands. As a consequence the percentage of oil recovered from the sands by present methods of oil production falls far short of the percentage which might be recovered if the expulsive force of the gas could be fully utilized.

When a single well is first opened to the flow of oil and gas there is produced an excessive amount of gas which is due primarily to the fact that gas travels more readily than oil over a large area to a point of decreased pressure. As a result of the excessive production of gas the gas pressure over the entire oil area or horizon declines more rapidly than the amount of oil produced would warrant.

I have devised a method of flowing oil from the oil sands constituting the oil pool

which enables the energy of the gas occurring with the oil in the oil sands to be utilized to the fullest advantage. According to my invention, a group of wells will be projected into the oil bearing sands over the entire oil area, the spacing of the wells preferably being such as will best suit the particular field to be developed. In the process of drilling, some of the wells may reach the oil producing sands ahead of others in which event such wells will be shut in for the time being or until all of the wells have reached the oil producing sands after which the entire group of wells will be opened simultaneously and allowed to flow oil and gas. By developing the field as I propose, that is to say, by opening all of the wells simultaneously, the gas pressure will be exerted on all of the wells and will result in a much greater oil production because neither the oil nor gas will have to travel an excessive distance to the well which is the point of decreased pressure and consequently the energy of the gas over the field and within the gas will be utilized to best advantage in moving oil to the well.

The oil in its natural condition in the sand contains a large quantity of dissolved gas, the amount of gas dissolved in the oil depending on the rock pressure. As set forth in a pending application I have discovered that oil containing natural gas in solution has a much lower viscosity than oil which contains no dissolved gas. It therefore follows that the oil in its natural condition is more mobile or fluid than is the case when the gas pressure has been released and the dissolved gas escaped from the oil. Other conditions being equal the force required to move a viscous liquid through capillary openings such as those which exist in an oil sand varies directly with the viscosity of the fluid.

While the wells are producing, there will be an area of decreased pressure in the vicinity of each well. When the wells have been producing until the pressure has fallen to a certain point it is proposed to shut-in all the wells in the field and allow the rock pressure to equalize over the entire oil horizon. By shutting in the wells the pressure over the entire field will have a tendency to equalize

and while this process is going on some oil will move into the area of decreased pressure which exists around the wells prior to shutting in. When, therefore, wells are again opened more oil will be available close to the well and a greater production of oil will be obtained than when they were shut in and this increased production will apply to all of the wells operating in the field. When the wells are closed in for the purpose of allowing equalization of pressure to take place some of the gas, more particularly that which exists in the vicinity of the well where the pressure is low, will be forced back into solution under the increase of pressure.

It is preferred to operate the wells under a controlled back pressure so that excessive quantities of gas will not be produced with the oil,—the ideal condition being such that the volume of gas produced with each barrel of oil would be equivalent to the gas dissolved in the oil under naturally occurring conditions.

In order to prevent the pressure on the field from declining too rapidly it is desirable to return to the oil sand the natural gas which is being produced with the oil. When the wells are operated under a back pressure, the pressure of the outgoing gas will be comparatively high and it will, therefore, be a comparatively simple matter to increase or boost the pressure of such gas sufficiently to enable it to be forced or injected into the oil sands. Additional gas taken from nearby fields can also be introduced into the sands while the wells are producing and after they are shut in to enable the pressure on the field to be brought up to the desired point which may be greater or less than the natural rock pressure. If natural gas is not available air may be used for the same purpose.

As the flow of oil tends to decrease quite rapidly and the pressure drops very rapidly after a field has been producing for some time, the economic cost of pumping gas may be so high that it will not be advisable to pump into the producing sand sufficient gas to raise the oil to the original rock pressure. Under such conditions the pressure would be raised by introducing gas only to a point sufficient to hold a desirable viscosity of the oil and to maintain the production. A gradual drop in pressure can be continued until all of the oil has been removed that is capable of being removed by flowing under the pressure of the oil and gas in the sand.

The back pressure which should be kept on the wells will depend upon various factors among which may be mentioned the porosity of the sands in which the oil and gas occur. In order to determine what back pressure should be maintained samples of the sands will be obtained and these samples subjected to laboratory tests to determine among other things the rate of migration of the oil and

gas through the sands under pressures approximating those in the oil field and what differential pressure should be maintained to produce the proper flow of oil, the tests being made with samples of oil and gas taken from the same field. The cores of the bores taken from the oil sand should be watched very carefully to be sure that the well opens into the most porous portion of the sand in order to give the oil the advantage of migration through the most porous portion.

Another factor which has an important bearing on the back pressure which should be kept upon the wells is the extent of reduction of the pressure which must be given in order to set free the potential energy of the gas in the oil. This pressure reduction preferably should be made as suddenly as possible in order to start a movement or effervescence of the gas in the oil. This effervescence or boiling of the gas tends to convert the oil into a foamy mass and carry the oil as foam toward the outlets of the well. If the pressure is reduced gradually the gas will come out of the oil without much effervescence. It is desirable therefore that the pressure changes should be manipulated so that as much effervescing or bubbling of the oil can be obtained as possible. This effervescence should take place not only at the opening of the well but back through the sands as far as practicable. Where there are a large number of openings all subject to the same pressure, the foamy oily mass has a better opportunity to reach a point of low pressure. The back pressure is maintained at the top of the well to prevent waste and to conserve the energy of the gas and oil. The highest possible back pressure should be maintained at the top of the well in order to recover gas at high pressure so that this high pressure gas may be returned to the oil sands. The higher the pressure of the gas recovered at the casing head the less power will be required in compressing it in order to raise its pressure sufficiently high to force it back into the sand. Accordingly, the pressure at the casing head may be reduced to substantially atmospheric pressure at the time the wells are opened, in order to start the effervescence or the sudden release of the gas from the oil and then the back pressure may be built up as soon as the foamy oil starts to raise through the wells.

Inasmuch as there will probably be considerable variation in the character of the sands in the same field it may be that some of the wells will tend to flow more gas than others. Such wells are preferably maintained under a higher back pressure than the other wells in order that the gas pressure may not be dissipated to the injury of the other wells or are shut in altogether. Furthermore if some of the wells should cease flowing oil such wells would be shut in.

In addition to the gas which goes back into solution in the oil on account of the equalization of pressure, the increased pressure resulting from forcing gas into the sands will cause additional volumes of gas to go into solution in the oil and thereby further increase its fluidity. Also there is obtained a greater explosive force when the oil wells are again opened due to the increased pressure in the vicinity of the wells.

From the foregoing description it will be readily appreciated that a simple and practical method of producing oil is provided, a method which enables the pressure of the gas on the field to be utilized in a most effective manner in the production of oil.

What is claimed is:

1. A method of developing an oil field comprising projecting a plurality of wells into an oil sand, preventing flow of gas and oil from any given well until all of the wells are ready for producing and then flowing the oil and gas from all the wells simultaneously.

2. A method of developing an oil field comprising projecting a plurality of wells into an oil sand, preventing flow of gas and oil from any given well until all of the wells are ready for producing and then flowing the oil and gas from substantially all the wells simultaneously under a back pressure.

3. In the method of claim 2 the steps of operating oil wells under a uniform back pressure and periodically reducing the pressure equally on all of the wells simultaneously.

4. A method of developing an oil field comprising projecting a plurality of wells into an oil sand, preventing flow of gas and oil from any given well until all of the wells are ready for producing, then flowing the oil and gas from substantially all the wells simultaneously, and shutting in any well which subsequently flows more gas than other wells.

5. In the method of claim 1 the steps comprising allowing all of the wells to flow oil and gas until the gas pressure falls to a predetermined point, thereafter shutting in all of the wells until the pressure remaining in the sands has equalized over the entire field, and again opening the wells.

6. In the method of claim 1 the steps comprising allowing all of the wells to flow oil and gas until the gas pressure falls to a predetermined point, thereafter shutting in all of the wells and restoring pressure over the entire oil area by injecting a gaseous fluid into the oil sands.

7. A method of developing an oil field comprising projecting a plurality of wells into an oil sand, allowing all of the wells to flow oil and gas under a back-pressure until the gas pressure falls to a predetermined point and then shutting in the wells, pumping a gaseous fluid into the field to bring the pressure in the oil sands up to a predetermined

point, and again opening all of the wells simultaneously.

8. A method of developing an oil field comprising projecting a plurality of wells into an oil sand and allowing all of the wells to flow oil and gas, restoring to the field the natural gas coming from the flowing wells, shutting in the wells when the gas pressure falls to a predetermined point, pumping into the field a gaseous fluid under pressure until the pressure in the field has reached a predetermined point, and again opening all of the wells.

9. In the method of claim 2, the steps of maintaining such back-pressure on the wells so that substantially the same ratio between oil and gas flowing from the wells is maintained at all of the wells.

10. A method of developing an oil field comprising projecting a plurality of wells into an oil sand, maintaining such back-pressure on the wells that substantially the same ratio between oil and gas flowing from the well is maintained at all of the wells, and shutting in such wells as produce an excess of gas.

11. In the method of claim 2, the steps of maintaining such back pressure on the well that substantially the same production ratio between oil and gas is maintained at all of the wells, shutting in the wells when the gas pressure reaches a predetermined point and allowing the pressure in the field to equalize.

12. In the method of claim 2, the steps of maintaining such back pressure on each of the wells that substantially the same production ratio between oil and gas is maintained at all of the wells, shutting in such wells as produce an excess amount of gas, and increasing the pressure in the oil sands by pumping a gaseous fluid into the field.

13. In the method of claim 2, the steps of maintaining a controlled back-pressure on the wells such that a definite production ratio between oil and gas is maintained at each of the wells, restoring to the field the natural gas flowing from the wells, and shutting in any well which produces an excess quantity of gas.

14. A method of developing an oil field comprising projecting a plurality of wells into an oil sand, maintaining such back-pressure on each of the wells that a substantially uniform production ratio between oil and gas is maintained at all of the wells, restoring to the field the natural gas flowing from the wells, shutting in any well which produces an excess quantity of gas, finally shutting in all of the wells, increasing the pressure over the entire field by pumping into the same a gaseous fluid under pressure, and again opening all of the wells simultaneously.

15. In the method of claim 2 the steps of maintaining such back-pressure on each of the wells that a substantially uniform pro-

duction ratio between oil and gas is maintained at all of the wells, restoring to the field the natural gas flowing from the wells, shutting in any well which produces an excess quantity of gas, finally shutting in all of the wells, increasing the pressure over the entire field by pumping into the same a gaseous fluid under pressure, and thereafter opening all of the wells and allowing them to flow under a back-pressure.

16. A method of developing a new oil field comprising projecting a plurality of wells into an oil bearing sand, opening the wells to the flow of oil and gas, allowing the wells to flow until more gas is flowing than would ordinarily flow if only that gas which is dissolved in the oil constitute the explosive force, shutting in the wells, increasing the gas pressure in the field sufficiently to redissolve the natural gas in the oil in the oil sand, and thereafter opening the wells simultaneously to the further flow of oil and gas.

17. A method of developing a new oil field comprising projecting a plurality of wells into an oil sand in spaced relation throughout substantially the entire oil sand area, preventing flow of oil from any of the wells until all the wells are ready for production, and opening all of the wells simultaneously to the flow of oil and gas.

In testimony whereof I affix my signature.
